FIG. 1

FIG. 2

FIG. 3

FIG. 4

FIG. 1 is a side perspective view of a double buckle for twin safety belts showing my new design, one of the two tongue portions being shown at the top in broken lines, the other being omitted for convenience of illustration. The broken lines below the buckle are mounting arms shown for purposes of illustration. The side opposite to that shown is reversely similar.

FIG. 2 is a top plan view of the design shown in FIG. 1, with the tongue portion omitted.

FIG. 3 is a side view as seen from the bottom of FIG. 2.

FIG. 4 is a side view as seen from the top of FIG. 2.

I claim:
The ornamental design for a double buckle for twin safety belts, substantially as shown and described.
